D. PORTER & S. K. OLIVER.
YARN TWISTING MECHANISM.
APPLICATION FILED FEB. 13, 1913.

1,081,328.

Patented Dec. 16, 1913.

UNITED STATES PATENT OFFICE.

DANIEL PORTER, OF NEW BROOKLAND, AND SEWALL K. OLIVER, OF COLUMBIA, SOUTH CAROLINA.

YARN-TWISTING MECHANISM.

1,081,328.

Specification of Letters Patent.

Patented Dec. 16, 1913.

Application filed February 13, 1913. Serial No. 748,140.

To all whom it may concern:

Be it known that we, DANIEL PORTER and SEWALL K. OLIVER, citizens of the United States, and residents of New Brookland, in the county of Lexington, and Columbia, in the county of Richland, respectively, in the State of South Carolina, have invented certain new and useful Improvements in Yarn-Twisting Mechanism; and we do hereby declare the following to be a full, clear, and exact description of the same, reference being had to the accompanying drawings, forming part of this specification, and to the figures and letters of reference marked thereon.

This invention relates more particularly to yarn twisting mechanism, making use of what is known as ring twisters, which effect the twisting of the yarn as the same is fed to the bobbins or spindles, and it has for its object to provide an improved means for guiding, feeding and combining the strands during their passage from the creel spools to the spindles, whereby the quality of the yarn will be improved, the production of corkscrew or irregularly twisted yarn prevented, production increased and labor cost decreased.

A further object of the invention is to provide a device which, while operating to feed and combine the single yarns between the creel frame and spindles, will serve as a stop motion in any case where a thread breaks at a point in advance of the spindle and after leaving the roller, whereby waste is prevented and whereby the broken thread is prevented from flying loose to interfere with other yarns.

A further object of the invention is to provide an apparatus in which the necessity for employing weight rollers is overcome with the advantage that on very fine yarns the rolls never become bruised by rough contact with each other, and whereby the danger of the yarn being nipped between the rolls and fed irregularly or broken is avoided, as well as all danger of the yarn being fed over unused portions of the rolls, whereby it would be liable to be rendered dirty, greasy or rusty.

A further object of the invention is to provide a structure which may be "doffed" without stopping the spindles or mechanism and which will likewise permit of any yarn

being threaded or coupled up when broken or when a new spindle is to be started in action without the necessity of stopping the machine or in any wise interfering with the operation of other spindles.

Referring to the accompanying drawings, Figure 1 is a fragmentary elevation, partly diagrammatic of a portion of a yarn twisting machine embodying the present improvement; Fig. 2 is an end elevation of the parts illustrated in Fig. 1.

Like letters of reference in the several figures indicate the same parts.

In said drawings, the creel spools are diagrammatically represented at A, the spindles are indicated at B, the bobbins on the spindles at C and the ring spinners at D, each of the latter, of course, embodying a traveler of ordinary or preferred construction which is adapted to rotate on its ring or guide around the bobbin. The spindles are driven as usual from a roller by belts passing around the spindle pulleys b and the individual strands or yarns are fed from the creel spools through guides or eyes E in each of which the desired number of individual yarns are brought into proximity or together, thence around feeding and guiding rollers to be presently described, thence through eyes or guides F, and to the ring travelers. The feeding and guiding rollers, the construction and operation of which constitute the leading novelty in the combination forming the present invention are preferably two in number, each independent of the other and each journaled separately in bearings such as indicated at G. The two rollers lettered H and I are spaced apart an appreciable distance, one of the rollers, usually the forward and larger roller H, and preferably both of the rollers, being positively driven by suitable driving mechanism (not shown) to rotate in the same direction.

The yarns leading from the eyes E are passed around the two rollers a number of times so as to include said rollers in a series of single loops, it being essential to the invention that the several loops shall be kept separate or spaced from each other for which purpose one at least of the rollers is provided with a series of grooves such as h, and the yarn is led around the rollers so that the successive loops enter and are guided by the succeeding grooves passing

2
from the last groove to the eyes F and thence to the ring spinners.

Obviously if one only of the rollers is a driven roller, the other roller will be driven entirely by the engagement of the yarns therewith, in which case it may be subdivided to form in effect a series of small light rollers as indicated for example by the dotted lines i, in Fig. 1, but ordinarily 10 as above stated in the preferred construction both rollers are driven positively and at a speed to feed the yarns at the same rate. In the example illustrated while the roller H is shown of larger diameter than the 15 roller I, the grooves are of such depth that the diameter at the bottom of the grooves corresponds to the diameter of the roller I and both rollers are positively driven at the same speed. With this arrangement each 20 loop of the yarn is subjected to uniform tension or pull, and each separate yarn will be fed at a uniform rate to the spindle bobbin.

Owing to the fact that the loops passing 25 around the two rollers are kept separate from each other, if the end of the yarn next the spindles has no tension whatever upon it, as, for instance, when it is hanging freely, the loops will be sufficiently loose to 30 prevent any feeding of the yarn by the rotation of the rollers, but the slightest tension on the end of the yarn, at once causes a tightening of the loops around the rollers, with the result that the yarn is positively 35 fed, thereby relieving the ring spinner from all work save the maintenance of a very slight tension on the yarn. It follows also that the breaking of a yarn at once arrests its feed so that there is no liability of the 40 yarn becoming snarled up or in any way interfering with the feed of adjacent yarns or the operation of other spindles. It also follows that the bobbin or any spindle may be "doffed" without stopping the operation 45 of the rolls, and the yarns may be passed around the rolls in the easiest and simplest way when it is desired to start a new spindle in operation, while the rollers are in motion, the operator having simply to wind 50 the yarn around the two rollers in loose loops each in its appropriate groove, allowing the end to be free or being kept loose

until it is threaded through the traveler and properly attached to the bobbin.

Practical operation demonstrates that 55 with an apparatus such as herein described better and more uniform results are secured, with no waste from snarling; the use of all weight or gravitating rollers is avoided and there is no danger of the yarn being nipped 60 between contacting rollers and fed irregularly, or fed at all when the ring traveler is not in operation.

Having thus described our invention, what we claim as new and desire to secure 65 by Letters Patent of the United States, is:

1. The combination with the series of spindles, rings and travelers, the creel and yarn guide eyes between the creel and travelers, of yarn feeding mechanism intermediate the yarn guide eyes embodying a long horizontal positively driven roller, a corresponding second roller spaced therefrom, said rollers both coöperating with the yarns 70 for a series of spindles and being mounted 75 in fixed bearings and out of frictional contact with other rollers and adapted to both be included in a succession of spaced loops of yarn between the creel and each spindle, respectively, and means for maintaining the 80 individual loops of yarn spaced from each other.

2. The combination with the spindles, rings, travelers, creel and yarn guide eyes between the creel and travelers, of yarn feeding mechanism intermediate the creel and travelers embodying a pair of proximate positively driven rollers each having a free and unobstructed space around the same, whereby the yarn may be freely 85 wrapped in loops around the two rollers, one of said rollers having a series of grooves therein, each for the reception of a single loop of yarn, whereby the individual loops 90 will be spaced from each other, the yarn 95 engaging portions of the two rollers being of the same diameter whereby the yarn will be fed uniformly by both rollers.

DANIEL PORTER.
SEWALL K. OLIVER.
